Primary Examiner — Katherine Glennon

(57) **CLAIM**

The ornamental design for a watch dial, as shown and described.

DESCRIPTION

2.1 is a front perspective view of a part of a watch dial, showing my new design;
 2.2 is a front view thereof;
 2.3 is a back view thereof;
 2.4 is a right-side view thereof;
 2.5 is a left-side view thereof;
 2.6 is a top view thereof;
 2.7 is a bottom view thereof;
 3.1 is a front perspective view of a part of a watch dial, showing my new design;
 3.2 is a front view thereof;
 3.3 is a back view thereof;
 3.4 is a right-side view thereof;
 3.5 is a left-side view thereof;
 3.6 is a top view thereof; and
 3.7 is a bottom view thereof.

The broken lines in the reproductions show portions of the watch dial that form no part of the claimed design.

1 Claim, 14 Drawing Sheets(56)
